CYCLE SADDLE

Robert C. Persons, 72 Commercial St.,
Worcester, Mass. 01608

Filed Mar. 17, 1967, Ser. No. 6,270

Term of patent 14 years

(Cl. D90—16)

FIG. 1

FIG. 2

FIG. 1 is a plan view of a cycle saddle showing my new design, and

FIG. 2 is a view in side elevation thereof, looking in the direction of arrow 2 in FIG. 1.

The dominant features of my design reside in the portions shown in full lines, and the characteristic feature thereof resides in the two stripes having a contrasting color which are placed off-center to the longitudinal dimension of the cycle saddle, as shown.

I claim:

The ornamental design for a cycle saddle, as shown and described.
